UNITED STATES PATENT OFFICE.

ALLEN SHERWOOD, OF SYRACUSE, NEW YORK.

HARNESS.

SPECIFICATION forming part of Letters Patent No. 333,556, dated January 5, 1886.

Application filed November 6, 1885. Serial No. 182,047. (No model.)

To all whom it may concern:

Be it known that I, ALLEN SHERWOOD, a citizen of the United States, residing at Syracuse, in the county of Onondaga and State of New York, have invented certain new and useful Improvements in Harness, of which the following is a specification, reference being had therein to the accompanying drawings.

My invention relates to that class of worker-harness which employs a yoke supported beneath the horses, and connected by short traces to the hames, and serving for the connection of the draft-chain between the horses, thereby dispensing with the use of ordinary traces, rendering the control of plows much easier, and obviating injury to shrubbery and trees by outside traces and projecting single trees, providing a harness which is as well adapted for use in connection with wagons, sleighs, stone-boats, and drags, as well as other vehicles; and my invention consists in certain features of construction of the yoke, consisting of a single piece of steel carrying an evener-chain and pulley duly inclosed, as hereinafter described, and the novel features of which are specially set forth in the claims.

Referring to the drawings, Figure 1 is a perspective view of the yoke carrying evener traces and pulley, forming the main parts of the harness. Fig. 2 is a perspective of a portion of one end of the yoke, a portion of one end of the chain-traces, a portion of the back-strap, and its snap-buckle hooked to the end of said yoke. Fig. 3 is a transverse vertical section of the yoke, its pulley, and cap-plate at the point where it is united to the middle of the yoke. Fig. 4 is a top view of the central portion of the yoke, its pulley, and cap-plate.

In said drawings, the yoke is represented at A. It is made of spring-steel, arched upward in the center and in the opposite direction on each side thereof, and properly tempered, and on top of the arch is secured the draw-plate B by means of rivets b⁶, and also of the bolt b, that furthermore forms the journal for the evener-pulley B², and fastens the handle b' on top of the draw-plate. This draw-plate forms also the cap for the evener-pulley B², and may be provided with a single ring or eye on the rear side, as shown in Fig. 4, to receive one end of a draft-chain, whereby means of connec-

tion with various implements are provided; but I prefer to provide the draw-plate with a horizontal bar, b², having series of notches b³, 55 to receive the end link or the hook of a draft-chain, either directly in the rear of the center of the yoke or on either side thereof, to give one horse some advantage over the other.

To prevent chafing of the horse against the metal of the yoke, the concave side of the latter is lined either with wood, leather, felt, or rubber F, secured thereto by rivets f.

To connect the yoke with the supporting back-strap G, and with the short traces H, an eye, K, is formed in each end of said yoke by cutting the metal of said yoke and separating it therefrom on three sides of said eye, but leaving the bottom portion uncut, and bending it outwardly at that point to form a tongue, k, of sufficient size and strength for the trace-links H to engage with. To retain said links upon the tongue k, a perforation, k', is made to receive a pin or split key, k², in front of the links H. This kind of eye and tongue may also be formed upon the ends of the curved single-tree shown in my patent of December 16, 1884.

To connect the back-strap G with the eyes K, said strap is provided at one end with a buckle, L, having two cross-bars, l and l', around 80 which the end of the back-strap is secured by passing it first in front of the bar l and then under the bar l', and up again to a point slightly higher than the bar l, to which it is secured by the front bar, l', and screws l³ at 85 each end of the latter. The lower end of the buckle is in the form of a hook, L', and in front of said hook the spring-bolt L² is retained at the lower end between the branches l⁴ of the frame of the buckle, while its upper end passes 90 loosely through an arm, l⁵, projecting forward from the bar l'. The middle portion of the bolt L² is bent to form a hooked handle, L³, to withdraw the bolt from its rest upon the hook L', and extending up from said handle is a 95 stem, around which the spring l⁶ is coiled and abuts against the arm l⁵ of the front bar of the buckle.

To guard against the loss of the split key, the latter is permanently attached by means of the chain k' to a perforated lug upon the buckle.

The opposite end of the back-strap G may also be provided with a snap-hook or buckle, as L, to connect it to the rings b⁴, permanently

secured to the yoke by the hooked lugs b^6 , projecting laterally from the cap or draw-plate B; but an ordinary narrow leather strap and buckle fastened to the inner end of the back-strap G will answer the purpose required, as it is seldom necessary to disconnect both ends of the back-strap from the yoke.

To connect the inner end of the back-strap to the yoke, the end of the above-stated narrow leather strap is easily passed under and through the ring b^4 , as said ring is retained loosely by the hooked lugs b^5 of the draw-plate and can be turned on its edge for that purpose.

Having now fully described my invention, 15 I claim—

1. In combination with the yoke A, the draw-plate B, provided with a bar, b^2 , having a series of notches, b^3 , substantially as and for the purpose described.

20 2. The combination of a steel yoke, consisting of a single bar of metal bent centrally in the form of an arch, with inverted arches on each side thereof, with a pulley upon the central arch, and a combined cap and draw-plate, substantially as and for the purpose described.

25 3. The combination of a yoke having an eye

cut out at each end, and a tongue, k , projecting outwardly therefrom, with traces engaged therewith, substantially as described.

4. The combination of a yoke having an eye 30 at each end with the back-strap G and buckle L, having a hook and spring-bolt, substantially as and for the purpose described.

5. The combination of a yoke having projecting therefrom a tongue, k , perforated at k' , 35 a pin, k^2 , therein, a back-strap, a buckle provided with a spring-bolt, and a chain connecting said buckle within the pin k^2 , substantially as and for the purpose described.

6. The combination of a yoke, consisting of 40 a single-tree bar bent centrally in the form of an arch, with a pulley upon said arch, and a combined cap and draw-plate provided with lugs b^5 and rings b^4 , substantially as and for the purpose described.

In testimony whereof I affix my signature in presence of two witnesses.

ALLEN SHERWOOD.
